UNITED STATES PATENT OFFICE.

HENRY SELBY HELE-SHAW AND THOMAS EDWARD BEACHAM, OF LONDON, ENGLAND.

HYDRAULIC PUMP AND MOTOR.

Application filed March 25, 1927, Serial No. 178,202, and in Great Britain April 26, 1926.

The present invention consists of an improved method of varying the stroke of hydraulic pumps or motors of the type in which a number of radial cylinders fitted with pistons and connecting rods working on a non-rotating crank cooperate with a cylindrical valve. In order to vary the stroke of such a machine it is necessary to provide a mechanism by means of which the crank can be moved relatively to the axis of rotation and it is necessary to ensure that at all times the axis of the crank shall be exactly parallel to the axis of rotation.

The present invention consists broadly of a hydraulic pump or motor of the kind having a rotary carrier provided with radial cylinders operating on a fixed crank carried by a sliding block movable radially to vary its throw, wherein the sliding block has laterally extending portions sliding between parallel plates arranged transversely to the axis of the pump or motor. The guide-way in which the crank pin carrying block slides may be formed in transversely arranged plate members secured at one side of the casing of the pump or motor and provided on its opposite side with a bearing on which one end of the cylinder carrier rotates.

According to a further feature of the invention in a hydraulic pump or motor of the kind having a rotary carrier provided with radial cylinders operating on a fixed crank of variable throw, the valve ports of the passages leading to the rear ends of the cylinders in a cup-shaped carrier extend through the sides of the shaft of the carrier into a bearing so as to register during the rotation of the shaft with inlet and outlet ports provided in such bearing.

A manner of carrying out the invention is illustrated by the accompanying drawings in which Figure 1 is a general sectional elevation of a rotary pump or motor to which the invention is applied, Figure 2 is a sectional view on line B—B Figure 1, the member carrying the guide-way in which the crank pin carrying block slides being omitted from the lower half of the figure.

In these drawings 2 is the crank pin of a rotary pump of the kind having a series of radial cylinders 5^a provided with truncated pistons 5^b connected by rods 5^c to the crank pin 2, the radial cylinders being carried by a cup-shaped carrier 5 of which the end 5^d is formed as a valve having ports 6 connected by a passage 7 to the ends of the closed ends of

the cylinders 5^a, the ports 6 registering during the rotation of the carrier 5 with ports 13^c in a boss 13^b formed on the fixed casing 13 of the pump or motor in the known manner, the valve 5^d being mounted on roller bearings 5^e, 5^f in the casing 13 and extended to form a driving or driven shaft 5^d. On the inner end of the carrier 5 is fixed by screws 8^a a bearing or journal plate 8^b.

In the present invention an extension 2^a of the crank pin 2 is fixed by a nut 2^b in a cross head or sliding block 10 sliding in a slotted or guide-way plate 11 normally to the plane through which the section is taken.

The slotted or guideway plate 11 is secured by bolts 11^a to the end plate 13^a of the casing 13 and the inner face of the end plate 13 is recessed and its base 13^c machined to form a plane at right angles to the axis of the pump or motor.

In the present example the lateral extensions of the sliding block 10 are in the form of a disc 12 provided with bearing faces 12^a and 12^b which fit accurately between the face 13^c of the end plate 13^a and the face 11^b of the guide-way plate 11.

On the inner face of the guide-way plate 11 is formed a boss 11^c which carries the inner race 11^d of a ball bearing 11^e, the outer race 11^f of the bearing being secured on the cylinder carrier 5.

The cross head or sliding block 10 is fitted with a rod 10^a secured therein by a nut 10^b and sliding in the direction of the slot of the guide-way of the plate 11 in a bearing 13^c in the casing 13, the bearing 13^c being provided with a fluid gland 13^d.

The cylinder carrier 5 may be made practically oil-tight by filling in the spaces between the cylinders and securing over its open end an annular ring 16. This enables the outer casing 13 to be run empty of oil as oil leaking past the pistons 5^b will fill the carrier 5 and be held within the ring 16 by centrifugal force.

In order to bore the cylinders 5^a without making an opening through their closed ends an opening 5^g is provided in the diametrically opposite side of the carrier 5 and fitted with a screwed plug 8.

In the example shown the valve rotates in a fixed seating, it may however be arranged as a sleeve rotating on a fixed cylinder.

In the above construction, the provision on the extension 12 of the sliding block 10 of widely disposed bearing faces 12^a and 12^b,

that is, constructing them in preferably oval form and with the length of the minor diameter considerably greater than that of the circle of the crank pin 2, enables the sliding block 10 to withstand any bending stress on the crank pin 2, and reduces wear in the guide-way of the guide-way plate 11.

What we claim and desire to secure by Letters Patent is:—

- 10 1. A hydraulic pump or motor comprising in combination, a fixed crank pin, a sliding block to which said pin is fastened, a guide-way plate fixed near the end of the motor casing, said plate having a faced bearing surface on its outer side and a slotted radially arranged guide-way for the sliding block, an outer plate forming the end of the pump casing and having its inner surface faced to form a bearing, a sliding plate having continuous bearing surfaces on its opposite faces integral with said block but disposed transversely to the axis of the pin, and slideable between the faced surfaces of the guide-way plate and the outer plate.
- 25 2. A hydraulic pump or motor comprising in combination, a fixed crank pin, a sliding block to which said pin is fastened, a guide-way plate fixed near the end of the motor casing, said plate having a faced bearing surface on its outer side and a slotted radially arranged guide-way for the sliding block, an outer plate forming the end of the pump casing and having its inner surface faced to form a bearing, a sliding disc having continuous bearing surfaces on its opposite faces integral with said block but disposed transversely to the axis of the pin, and slideable between the faced surfaces of the guide-way plate and the outer plate.
- 30 3. A hydraulic pump or motor comprising in combination, a fixed crank pin, a sliding block to which said pin is fastened, a guide-way plate fixed near the end of the motor casing, said plate having a faced bearing surface on its outer side and a slotted radially arranged guide-way for the sliding block, an outer plate forming the end of the pump casing and having its inner surface faced to form a bearing, a sliding disc having continuous bearing surfaces on its opposite faces integral with said block but disposed transversely to the axis of the pin, and slideable between the faced surfaces of the guide-way plate and the outer plate.
- 35 40 45 50

ing surfaces on its opposite faces integral with but disposed transversely to the axis of the pin, and slideable between the faced surfaces of the guide-way plate and the outer plate.

4. A hydraulic pump or motor comprising in combination, a rotary cylinder carrier, a fixed crank pin, a sliding block to which said pin is fastened, a guide-way plate fixed near the end of the motor casing, said plate on its inner face having a bearing for said rotary carrier and on its outer surface being formed with a faced bearing surface and being provided with a slotted radially arranged guide-way for the sliding block, an outer plate forming the end of the pump casing and having its inner surface faced to form a bearing, a sliding plate having continuous bearing surfaces on its opposite faces, said sliding plate being integral with said block but disposed transversely to the axis of the crank pin, and slideable between the faced surfaces of the guide-way plate and the outer plate.

5. A hydraulic pump or motor comprising in combination an integral rotary valve and cylinder carrier, a fixed crank pin, a sliding block to which said pin is fastened, a guide-way plate fixed near the end of the motor casing, said plate having on its inner face a bearing for the rotary carrier and on its outer surface having a faced bearing, said plate also being provided with a slotted radially arranged guide-way for the sliding block, the rotary cylinder carrier being closed at one end by the guide-way plate, the opposite end of the carrier forming a rotary valve having passages leading from the cylinders in the carrier to ports in the cylindrical face of the valve adapted to register with corresponding ports formed in the bearing supporting the valve, an outer plate forming the end of the pump casing and having its inner surface faced to form a bearing, a sliding disc having continuous bearing surfaces on its opposite faces integral with said block but disposed transversely to the axis of the pin and slideable between the faced surfaces of the guide-way plate and the outer plate.

In witness whereof we affix our signatures.

HENRY SELBY HELE-SHAW.
THOMAS EDWARD BEACHAM.
